UNITED STATES PATENT OFFICE.

HENRY M. CRANE, OF NEW YORK, N. Y., ASSIGNOR TO WESTERN ELECTRIC COMPANY, OF CHICAGO, ILLINOIS, A CORPORATION OF ILLINOIS.

MEASURED-SERVICE TELEPHONE-EXCHANGE SYSTEM.

SPECIFICATION forming part of Letters Patent No. 782,828, dated February 21, 1905.

Application filed August 31, 1903. Serial No. 171,346.

To all whom it may concern:

Be it known that I, HENRY M. CRANE, a citizen of the United States, residing at New York, in the county of New York and State of New York, have invented a certain new and useful Improvement in Measured-Service Telephone-Exchange Systems, of which the following is a full, clear, concise, and exact description.

My invention relates to the measurement of telephone-service, and has for its object to provide an improved organization of apparatus and circuits for the operation of a service-meter in association with each line at a telephone-exchange switchboard of the central-battery "two-wire" type—that is, where only two terminals and their connected conductors are provided for each multiple spring-jack instead of three, as has been common heretofore. The organization of a system of this type so as to retain the standard line-signals and supervisory signals of three-wire systems is a matter of considerable difficulty, and it has been impracticable in such systems heretofore devised to provide also in addition to such signals a service-meter associated with each line at the central switchboard to register each call for which a charge is to be made.

I have devised a two-wire system in which a service-meter is associated with each line, to be actuated in response to a switch associated with the operator's cord-circuit. This system is illustrated in the accompanying drawing, which is a diagram indicating a subscriber's line extending from a substation to a central office, with an operator's plug-circuit and a portion of the accessory apparatus, the system being organized and equipped in accordance with my invention.

The usual subscriber's apparatus is shown at the substation A, including a gravity telephone-switch *s*, controlling the circuit. At the central office the two line conductors 1 2 are connected to the armatures *c* *c'*, respectively, of a cut-off relay *c*. The back contacts of said armatures are connected to normal extensions 1^b 2^b of the line conductors leading to the poles of a central battery *b*. The pole of the battery which is so connected to conductor 1 is grounded, and a line-signal magnet

d, which may be a relay controlling a subsidiary lamp-signal *d'*, is included in the normal extension 2^b of the other line conductor, 2. The armatures *c* *c'* of the cut-off relay *c* are provided with front contacts connected with alternate extensions 1^a 2^a of the line leading to the contacts *d* *d'*, respectively, of the several multiple spring-jacks *a*. The magnet of the cut-off relay is connected in a branch to ground from the conductor 2^a to be excited when any jack is plugged into.

The operator is provided with a number of pairs of plugs *e* *e'*, such as the pair shown, for connecting lines together. Each plug has the usual tip and sleeve contacts *e* *e'*, adapted to register with the contacts *d* *d'*, respectively, of any spring-jack *a* into which such plug may be inserted. The tip and sleeve contacts of each plug are united with the corresponding contacts of its mate by link conductors 3 4, respectively, of the cord-circuit, each of said conductors including two windings of the usual repeating-coil. The central battery *b* is connected in a bridge of the cord-circuit between the windings of the repeating-coil, the grounded pole of said battery being on the side which is connected to conductor 3, leading to the tip-contacts of the plugs. Relays *f* *g* are included in the circuit of conductor 4 between the free pole of the battery and the answering and calling plugs, respectively, in the path of current through the cut-off relays of the respective lines to which said plugs may be connected. Said relays are adapted when excited to close local circuits through supervisory signal-lamps *f*² *g*², respectively. Supervisory relays *f'* *g'*, included in the cord-strand 3 between the battery and the answering and calling plugs, respectively, control short circuits 8 9 about the relay-magnets *f* *g*, respectively, so that when relays *f'* *g'* are excited relays *f* *g* are short-circuited and inert. Said relays *f'* *g'* are in the path of current controlled at the substation telephone-switches of the lines with which the corresponding plugs may be connected. The result is that when the plugs are in use the lamps *f*² *g*² indicate to the operator the condition of the connected lines, said lamps being lighted when the telephone-

switch is opened at the corresponding subscriber's station, as when the telephone is replaced on its hook for use.

In accordance with the present invention I provide in association with each line of a system such as illustrated a connection-register or service-meter *h* of the well-known type adapted to count or register each time current of the required strength is passed through its magnet. This service-meter is connected in the system illustrated in a branch 5 from the conductor 1 to contacts *a* of the multiple spring-jacks *a* and is short-circuited by extension 1^a of the line when cut-off relay *c* is actuated. The service-meter is also connected in a local circuit extending from the plug-circuit by way of conductor 5 to armature *c* of the cut-off relay and thence to the grounded pole of battery *b* by way of the back contact of said armature and extension-conductor 1^b. To operate the service-meter, a switch is provided in association with the operator's cord-circuit, said switch being adapted when actuated to connect a suitable source of current in circuit with the service-meter. In the system illustrated the said switch for operating the service-meter is a key *k* adapted for manual actuation by the operator, said key being adapted when operated to break the normal circuit of link conductors 3 4 and connect the free pole of battery *b* with the tip-contact *c* of the plug instead of with the sleeve-contact, as before, and also to connect the sleeve-contact through the relay *f* to earth. The relay *f* is cut out. If desired, an operator's position-meter *l* may be included in the conductor 6, which leads from the free pole of battery *b* through the alternate contacts of key *k* to the tip of the plug, so that this meter will be caused to count or register each time the key is depressed to register a call on a subscriber's meter and will serve both as a check upon the indications of the several subscribers' meters and also to indicate the amount of work performed by the operator.

The subscriber's service-meter may be arranged to act also as a relay in a well-known manner to close a contact when the service-meter is actuated. I have illustrated such a contact *h*' in association with the service-meter *h*, controlling a conductor 7, which leads from the free pole of battery *b* through a resistance *m* to the conductor 2^a, and so to the thimbles *a*² of the several multiple jacks, with which thimbles the sleeve-contact *c* of the operator's plug is adapted to register.

In the operation of the system illustrated the subscriber's service-meter is intended to be actuated after the subscriber has hung up his telephone at the end of a conversation. During connection with the line it is short-circuited as to currents from the bridged battery of the plug-circuit by the armature *c* and its front contact of the cut-off relay *c*, which

constitute a preventive device for rendering the meter unresponsive to the normal operating-currents of the line; but when the key *k* is depressed the connection of battery *b* with the plug-contacts is reversed, and the cut-off relay being in a ground branch from conductor 2^a no longer receives current, so that it allows its armatures to fall back. The service-meter *h* is then left in a ground branch 5 1^b from the conductor 1^a. Current is applied 75 from the free pole of battery *b* by way of conductor 6, leading through the operator's meter *l* and contacts of key *k* to the tip of the inserted plug and thence through the meter *h* and conductor 1^b to earth. Both meters *h* 80 and *l* are thus caused to register, and at the same time the closure of contact *h*' by the subscriber's meter *h* applies battery in the circuit 7 2^a to the sleeve of the plug and to earth through the relay *f*, whereby said relay is 85 excited and causes signal-lamp *f*² to be lighted. The flashing of this lamp when the key *k* is depressed serves as an indication to the operator that the subscriber's meter has been properly actuated. 90

The resistance *m*, cut-off relay *c*, and supervisory relay *f* are so proportioned to one another that the supervisory relay will be excited and the cut-off relay will remain inert when current is applied through said resistance *m*. 95

It will be noted that the subscriber's service-meter is well protected against accidental operation, since it is short-circuited when the line is in use, except at the instant of counting, and when the line is not in use the meter is protected by a "dead-ground" on the line side. 100

It is evident that any suitable return-conductor may take the place of the ground connections, and the claims should be read and understood accordingly. 105

I claim—

1. The combination with a telephone-line in a two-wire exchange switchboard-circuit, of a spring-jack for the line, a plug and plug-circuit, a service-meter connected with a contact of the spring-jack, a cut-off relay in a local branch circuit closed in making connection with the line, a shunt of the service-meter 110 closed by said relay when excited, a source of current, and a switch *k* associated with the plug-circuit, and connections for said switch adapted to render the cut-off relay inert and apply current to the service-meter when said switch is actuated, substantially as set forth. 115

2. The combination with a telephone-line extending from a substation to a central office, of a spring-jack for the line, a plug and plug-circuit for making connection therewith, a 120 source of current in the plug-circuit, a cut-off relay in a branch circuit closed in making connection with the line, a service-meter in series in one of the line conductors leading from the spring-jack, a shunt of the service-meter closed 125 130

by a contact of the cut-off relay when excited, a return-circuit for the service-meter established at a back contact of said cut-off relay, and a switch associated with the plug-circuit, 5 adapted to divert current from the cut-off relay and apply current in the service-meter circuit.

3. The combination with a metallic-circuit telephone-line extending from a substation to a central office, of a spring-jack for the line having two contact-terminals, a grounded central battery and a line-signal magnet, a cut-off relay having contacts normally connecting said battery and line-signal magnet with the 5 line, alternative connections of the line conductors to the respective spring-jack terminals, established by said cut-off relay when excited, a plug and plug-circuit having said central battery connected in a bridge thereof, a branch circuit including said cut-off relay connected between one of the spring-jack contacts and the grounded pole of the battery, a service-meter in a ground branch from the other contact of the spring-jack, said branch 5 being controlled at a back contact of said cut-off relay, a switch associated with the plug-circuit adapted to reverse the connections of the battery with the plug, whereby the cut-off relay is rendered inert and the service-meter actuated, and a supervisory signal device in the plug-circuit, controlled in the operation of said service-meter.

4. The combination with a telephone-line extending from a substation to a central office, 5 of a service-meter connected with the line, a preventive device for rendering the service-meter normally unresponsive to current in the line, means at the central office under the control of the operator for counteracting said preventive device to render the service-meter responsive, a source of current, and a switch for directing current from said source over the line to operate the meter.

5. The combination with a telephone-line, 5 of a service-meter connected in the circuit of the line, an electromagnetic switch, a circuit controlled thereby adapted to render said service-meter unresponsive to the normal operating-currents of the line, means for operating said switch to render said meter responsive, a source of current, and a switch adapted to apply current to the line to actuate said meter.

6. The combination with a telephone-line, 5 of a service-meter having a winding included

in the circuit of the line, a shunt-circuit of the service-meter adapted when closed to render the meter unresponsive to the normal operating-currents of the line, a relay adapted when operated to close said shunt-circuit, a winding for the relay connected with the telephone-line, a connection-switch for making connection with the line, an actuating-circuit for said relay completed in contacts of the connection-switch, switch-contacts controlling said actuating-circuit to render the relay inert, and other switch-contacts adapted to apply current to the line to operate the meter. 60

7. The combination with a telephone-line extending to a connection-terminal at a central office, of a plug and plug-circuit for making connection with the line at the terminal thereof, a service-meter connected with the line at the central office, switch-contacts actuated in making connection with the line controlling a circuit of the service-meter and adapted to render the same inoperative, switch-contacts associated with the plug-circuit and means controlled thereby adapted to bring the service-meter into operative relation with the 80 telephone-line, a source of current, and other switch-contacts of the plug-circuit for applying current to the line to actuate the service-meter. 75

8. The combination with a telephone-line 85 extending in two limbs from a substation to a connection-terminal at a central office, of a plug and plug-circuit for making connection with the line at the connection-terminal thereof, a battery in the plug-circuit, a relay having a winding in a branch circuit from one limb of the line closed to actuate the relay in making connection with the line, a service-meter having a winding connected with the other limb of the line, switch-contacts of the 90 relay controlling the circuit of the service-meter to render said meter inoperative during connection with the line, and a switch in the plug-circuit adapted to control the application of current to the line, whereby the relay may 95 be rendered inert to bring the service-meter into operative relation with the line, while current is applied to the service-meter to operate it. 100

In witness whereof I hereunto subscribe my 105 name this 29th day of June, A. D. 1903.

HENRY M. CRANE.
